ABSTRACT OF THE DISCLOSURE

A cap structure for containers adapted to dispense measured amounts of the contents from the container. This device employs a fixed cup member which is inserted into the neck of the container. A rotatable cup member is fitted into the fixed cup. Both of the cups are provided with openings in their bottoms and the rotatable cup is provided with a projection which functions as a stop and which extends into the opening in the fixed cup bottom. The device is also provided with a cover or cap which is threaded to the neck of the container and which is provided with a projection frictionally engaging the inside of the rotatable cup so that when the cover is screwed onto the neck of the container, the clutch enters the rotatable cup and rotates this cup to bring the opening in the bottom thereof into alignment with the opening of the bottom of the fixed cup, whereby the rotatable cup may be filled with liquid or granular material from the container through the aligned openings when the container is inverted. In order to capture the contents in the rotatable cup, the cover is turned through less than one revolution so that the opening in the rotatable cup is brought out of alignment with the opening in the fixed cup. Thereafter, the container may be turned right side up and the contents of the rotatable cup exposed upon removal of the cover from the container.

Description of the invention

This invention relates to measuring and dispensing closures for containers of liquid or granular material.

An object of this invention is to provide an improved container closure for measuring and dispensing the contents thereof which is economical to manufacture and which is efficient in operation.

Another object of this invention is to provide an improved measuring and dispensing closure for product containers which is provided with a rotatable cup member that is adapted to be filled with a portion of the contents of the container when the container is inverted and which portion of contents is adapted to be dispensed therefrom when the container cover is removed.

Another object of this invention is to provide an improved measuring and dispensing closure for a product container which comprises a fixed cup positioned in the neck of the container and a rotatable cup positioned in the fixed cup, said cups having openings in the bottoms thereof which are adapted to be aligned so that the rotatable cup may be filled with a portion of the contents of the container, said openings being adapted to be closed after said rotatable cup is filled so that the contents of the rotatable cup may be dispensed therefrom when the cover of the device is removed.

Other and further objects of this invention will be apparent to those skilled in the art to which it relates from the following specification, claims and drawing, in which, briefly:

FIG. 1 is a vertical sectional view showing an embodiment of this container closure device;

FIG. 2 is an exploded view showing the parts of this device;

2

FIG. 3 is a top view of this device with the cover thereof partially broken away to show the rotatable inner cup of the device with the opening in the bottom thereof aligned with the opening in the bottom of a fixed cup positioned in the container neck; and

FIG. 4 is a view similar to FIG. 3 showing the opening in the bottom of the rotatable cup out of alignment with the opening in the bottom of the fixed cup.

Referring to the drawing in detail, reference numeral 10 designates a container for liquid or granular material. This container may be in the shape of a bottle provided with a neck having threads 10a molded into the exterior surface thereof. A cup 11 which may be of plastic or like material fits snugly into the neck of the container and is held therein by friction. The cup 11 is provided with a flange 12 at the upper end thereof which overlaps the top of the bottle so that the cup 11 cannot be pressed further into the bottle than the neck thereof. The cup 11 is provided with an opening 12a in the bottom. This opening may be made slightly larger than a semicircle, as shown, or it may be made substantially smaller. Also, more than one opening of different shapes may be employed, if desired.

A rotatable cup 13 is positioned in the fixed cup 11 and fits closely therein. The rotatable cup 13 is provided with an opening 13a in the bottom thereof which is adapted to be aligned with the opening 12a of the fixed cup 11. The bottom of cup 13 is provided with a projection 15 which is adapted to extend into the opening 12a of the cup 11 and engage the sides thereof so it functions as a stop. Projection 15 therefore limits the rotation of cup 13 with respect to cup 11. Cup 13 is also made of plastic or other semi-flexible material and is provided with a flange 14 which is adapted to be pressed into the groove 12b of the cup 11 so that the rotatable cup 13 may not be readily removed from the fixed cup 11.

The cap 16 of this device is provided with an internal thread 16a which is adapted to engage the thread 10a of the container 10 when the cap 16 is applied to the container to close the mouth thereof. Cap 16 is provided with a circular clutch 17 on the inside thereof which is adapted to extend into the top of the rotatable cup 13 and frictionally engage this cup when the cap is threaded to the top of the container. Thus, when the cap 16 is rotated clockwise and screwed onto the container, as indicated by the arrows shown in FIG. 3, the clutch 17 enters the rotatable cup 13 after the cap is positioned well on the container. Clutch 17 then grips cup 13 and rotates it clockwise an amount determined by the projection 15 so that the opening 13a in the bottom of cup 13 is positioned over the opening 12a of cup 11. When cap 16 is to be removed from the container, it is rotated counterclockwise, as shown by the arrows in FIG. 4. During the initial part of the cap removal clutch 17 also grips the inner surface of rotatable cup 13 and this cup is rotated in the counterclockwise direction so that the opening 13a in the bottom thereof is brought out of alignment with the opening 12a of the fixed cup 11 and held there since the stop 15 engages one of the sides of the opening 12a. When the cap 16 is positioned all the way on the container the openings 13a and 12a of rotatable cup 13 and fixed cup 11, respectively, are brought into alignment and the cavity in rotatable cup 13 may be filled with a portion of the contents of the container 10 simply by inverting the container and allowing the contents to flow into cup 13. At the same time, clutch 17 seals the mouth of the cup 13 and prevents any of these contents from flowing past this cup and between the flange 12 and the cover 16. The cover 16 is then rotated counterclockwise in the direction indicated by the arrows in FIG. 4 while the container 10 is inverted so that rotatable cup 13 is rotated and the opening 13a

70

thereof closed by the bottom of cup 11, whereby a portion of the contents of the container is captured in rotatable cup 13 and held therein when the container is turned right side up. The cap 16 may then be removed all the way and the contents of cup 13 emptied by tilting the container. The skirt of the cap 16 may be made long enough so that the cap is big enough to receive the contents of cup 13 in case the cap 16 is completely unscrewed from the container while the container is inverted so that the contents of cup 13 will not be spilled accidentally.

While I have shown a preferred embodiment of the invention, it will be apparent to those skilled in the art that the invention is capable of variation and modification from the form shown so that the scope thereof should be limited only by the proper scope of the claims appended hereto.

What I claim is:

1. In a measuring and dispensing closure for containers of liquid or granular material, the combination comprising a fixed cup positioned in the neck of the container and frictionally held therein to prevent rotation thereof, said cup having an opening in the bottom thereof, a rotatable cup positioned in said fixed cup, said rotatable cup also having an opening in the bottom thereof which is adapted to be aligned with the opening in said fixed cup, said rotatable cup having stop means which determines the angle of rotation thereof, said stop means being positioned so that it limits the angle of rotation of said rotatable cup in one direction so that the openings in said cups are aligned, said stop means also limits the angle of rotation 30 of said rotatable cup in the opposite direction so that the openings in said cups are out of alignment and the bottoms of said cups are closed, a cap for said container, said cap having a clutch frictionally engaging said rotatable cup so that said rotatable cup may be rotated by rotating said cap whereby the opening in said rotatable cup may be aligned with the opening in said fixed cup when said cap is rotated in one direction and said openings may be brought out of alignment when said cap is rotated in the opposite direction.

2. In a measuring and dispensing closure for containers of liquid or granular material, the combination as set forth in claim 1 further characterized in that said clutch comprises an annular member attached to the inside of said cap and adapted to engage said rotatable cup frictionally.

3. In a measuring and dispensing closure for containers of liquid or granular material, the combination as set forth in claim 1 further characterized in that said stop means extends into the opening in the bottom of said fixed cup and is adapted to engage the sides thereof to limit the rotation of said rotatable cup with respect to said fixed cup.

4. In a measuring and dispensing closure for containers of liquid or granular material, the combination as set forth in claim 1 further characterized in that said fixed cup is provided with a flange at the top thereof to limit the distance said fixed cup is inserted into the neck of said container.

5. In a measuring and dispensing closure for containers of liquid or granular material, the combination as set forth in claim 1 further characterized in that said rotatable cup is made of flexible material and is provided with a flange on the outside thereof, said flange being pressed into a recess on the inside of said fixed cup for retaining said rotatable cup in said fixed cup.
